G. H. ROLFES

BURNER FOR HAND LANTERNS

Filed April 13, 1923

FIG. V

INVENTOR
George H. Rolfes
BY Cook & McCaulay
ATTORNEYS

UNITED STATES PATENT OFFICE.

GEORGE H. ROLFES, OF ST. LOUIS, MISSOURI, ASSIGNOR TO HANDLAN-BUCK MANUFACTURING COMPANY, OF ST. LOUIS, MISSOURI, A CORPORATION OF MISSOURI.

BURNER FOR HAND LANTERNS.

Application filed April 13, 1923. Serial No. 631,806.

To all whom it may concern:

Be it known that I, GEORGE H. ROLFES, a citizen of the United States of America, a resident of the city of St. Louis, in the State of Missouri, have invented certain new and useful Improvements in Burners for Hand Lanterns, of which the following is a full, clear, and exact description, reference being had to the accompanying drawings, forming a part of this specification.

This invention relates generally to improvements in lamp or lantern burners, and particularly to a burner intended for use in a hand lantern of the type used by persons engaged in the operation of railroad trains, the main object of the invention being to produce a burner which is provided with means whereby oil within the burner is prevented from escaping from said burner through the openings in the wall thereof through which the wick-operating stem of said burner extends.

As is well known, certain of the persons engaged in operating a railroad train are provided with hand lanterns which are used to give signals to other members of the crew of said train. The signals mentioned are given by swinging the lantern in a predetermined manner, and it is quite obvious that the oil in said lantern would be greatly agitated as a result of the motion of the lantern. The lantern burners in general use prior to the present invention were each provided with a toothed wheel mounted on a stem which extended transversely of the burner and passed through openings in the wall of said burner. The toothed wheel mentioned was in contact with the wick of the burner, and when it was desired to elevate or lower said wick it was only necessary to rotate said stem.

In giving signals with a hand lantern provided with a burner of the type used prior to this invention, it quite frequently happened that the oil within the lantern was agitated to such extent that some of said oil found its way through the openings in the wall of the burner through which the wick-adjusting stem extended, and the presence of this oil outside of the burner was a source of danger as there was always a liability that said oil might be ignited by the flame within the lantern.

The burner disclosed in the present application is so constructed and arranged that

oil is prevented from passing through the single opening through which the wick-adjusting stem extends whereby the objections recited above are eliminated.

With the foregoing and other objects in view, the invention comprises the novel construction, combination and arrangement of parts hereinafter more specifically described and illustrated in the accompanying drawings, wherein is shown the preferred embodiment of the invention. However, it is to be understood that the invention comprehends changes, variations and modifications which come within the scope of the claims hereunto appended.

Fig. I is a side elevation of a hand lantern provided with my improved burner, a portion of said lantern being broken away to show said burner, and the bail of the lantern being broken away to utilize space.

Fig. II is an enlarged horizontal section through the burner shown in Fig. I.

Fig. III is a section on line III—III of Fig. II.

Fig. IV is a view partly in vertical section and partly in elevation of the burner.

Fig. V is a section on line V—V of Fig. IV.

In the drawing, A designates a hand lantern which comprises the usual frame B, oil font C, hood D, chimney E and bail F, all of said parts being constructed in the ordinary way and assembled in the usual manner to produce a hand lantern of the type used for many years. The oil font C is provided with a cover plate G which is provided with a central aperture adapted to receive the burner H.

The burner H, disclosed in the present application, comprises a body portion 1 in the form of a cylindrical shell, and a cover member 2 which encloses the upper end of said body portion 1. Formed in the bottom wall of the body portion 1 is an aperture 3 and formed in the cover member 2 is a similar aperture 4 in alignment with the aperture 3. Arranged vertically through the body portion of the burner and extending upwardly therefrom is a wick-guiding tube 5, said tube being soldered or otherwise secured in place in the openings 3 and 4, so that a passageway is provided through said burner through which the wick W passes.

Arranged transversely of the body portion 1 of the burner is a wick-adjusting

stem 6, said stem being extended through an opening 8 in the wall of the body portion of the burner and projected outwardly therefrom, said stem being provided at its 5 outer end with an operating disk 7, and at a point within the burner with a toothed wheel 6' adapted to contact with the wick W to adjust said wick vertically. Supported within the body portion 1 of the 10 burner by frictional engagement with a wall thereof, or in any other suitable manner, is a member 9 which supports the wick-adjusting stem 6, said member being curved to correspond to the curvature of the wall 15 of the body portion of the burner and being provided with inwardly turned flanges 9' to add rigidity to said member. The ends of the member 9, as will be seen by referring to Fig. II, are bent away from the 20 wall of the body portion of the burner, one of said ends being provided with a circular opening 10 through which the inner end portion of the stem 6 extends, and the opposite end of said member being provided 25 with an open end slot 11 (Fig. III). The stem 6 is supported in the circular opening 10 and the slot 11.

Interposed between the slotted end of the member 9 and the adjacent portion of the 30 wall of the body portion of the burner is a body of packing 12, said packing being wedged in place and being intended to provide a comparatively tight fit between the stem 6 and the wall of the opening 8 and 35 thereby prevent oil within the burner from escaping through said opening 8 in the wall of the burner through which said stem passes.

As an added precaution to prevent the 40 leakage of oil around the stem 6, I employ a sleeve 13 which surrounds a portion of said stem. The sleeve 13 may be made in two parts as shown in Fig. V, and these parts are soldered together at their longitudinal meeting edges whereby a complete 45 sleeve is produced; or said sleeve may be made in one piece. The outer end of the sleeve 13 is closed except for an opening just large enough to permit the passage 50 therethrough of the stem 6. The sleeve 13 is packed inside with packing material 14 and is soldered to the outer face of the wall of the burner adjacent to the opening 8, and said packing material, fitting closely around the 55 stem 6 which passes through said sleeve, will prevent the leakage of oil around said stem and through said sleeve. By making the sleeve 13 in two parts as described, it is plain that I may apply one of said 60 sleeves to a burner without removing the associated operating disk 7; and this is desirable when one of said sleeves is applied to a burner already in use, the operating disk 7 of which is firmly fixed to the associated wick-adjusting stem.

The lantern burners in general use prior to this invention, as already stated, were each provided with a pair of aligned openings through which the wick stem of said burner passed, and when one of these burners is provided with the packing means disclosed in the present application, one of said openings is sealed up by means of a cap which is soldered, or otherwise secured, over said opening to prevent the leakage 75 of oil therethrough.

While I have described my invention as being intended particularly for use on lanterns of the type used by operators of railroad trains, it is apparent that said invention may be used with any lantern or lamp which is subjected to agitation which would tend to cause a leakage of oil around the wick-adjusting stem.

I claim:

1. A lantern burner comprising a body portion, a wick passing through said body portion, a stem for adjusting said wick, said stem being extended through an opening in the wall of said body portion, a member arranged on the inside face of the wall of said body portion and spaced apart in a horizontal direction from that portion of the wall of said body portion adjacent to said opening, and packing material interposed between said wall of said body portion and said spaced apart member whereby oil is prevented from passing through said opening.

2. A lantern burner comprising a body portion, a wick passing through said body portion, a stem for adjusting said wick, said stem being extended through an opening in the wall of said body portion, a stem-supporting member secured to the wall of the body portion of the burner, and packing material arranged adjacent to said opening and retained in place by said stem-supporting member whereby oil is prevented from passing through said opening.

3. A lantern burner comprising a body portion, a wick passing through said body portion, a stem for adjusting said wick, said stem being extended through an opening in the wall of said body portion, a stem-supporting member secured to the wall of said body portion, and packing material interposed between said wall of said body portion and a portion of said stem-supporting member at a point adjacent to said opening whereby oil is prevented from passing through said opening.

4. A lantern burner comprising a body portion, a wick passing through said body portion, a stem for adjusting said wick, said stem being extended through an opening in the wall of said body portion, a stem-supporting member secured to the wall of said body portion and having end portions which embrace said stem, and packing material in-

terposed between said wall of said body portion and an end portion of said stem-supporting member, said packing material being located adjacent to said opening in the 5 wall of said body portion whereby oil is prevented from passing through said opening.

5. A lantern burner comprising a body portion, a wick passing through said body portion, a stem for adjusting said wick, said stem being extended through an opening in the wall of said body portion and projected outwardly therefrom, said opening in the 10 wall of said body portion being of much greater diameter than said stem, a hollow member fixed to the outside face of the wall of said body portion adjacent to said opening and surrounding a portion of said stem, the inside diameter of said hollow member 15 being approximately the same as said opening, and packing material within said hollow member whereby oil is prevented from passing through said opening.

6. A lantern burner comprising a body 20 portion, a wick passing through said body

portion, a stem for adjusting said wick, said stem being extended through an opening in the wall of said body portion and projected outwardly therefrom, a stem-supporting member secured to the wall of said body portion at the inside face thereof and having end portions which embrace said stem, packing material interposed between said wall of said body portion and an end portion of said stem-supporting member, 30 said packing material being located adjacent to said opening in the wall of said body portion, an elongated hollow member comprising a plurality of parts secured together and secured to the outside face of 35 the wall of said body portion adjacent to said opening therein and surrounding a portion of said stem, and packing material within said elongated hollow member whereby oil is prevented from passing 40 through said opening.

In testimony that I claim the foregoing I hereunto affix my signature.

GEORGE H. ROLFES.
